UNITED STATES PATENT OFFICE.

JOHN P. NISSEN, OF PHILADELPHIA, PENNSYLVANIA.

DESIGN FOR HOSIERY.

• 57,540.

Specification for Design.

Patented Apr. 12, 1921.

Application filed December 1, 1920. Serial No. 427,632. Term of patent 14 years.

To all whom it may concern:

Be it known that I, JOHN P. NISSEN, a citizen of the United States, resident at Philadelphia, in the county of Philadelphia and State of Pennsylvania, have invented a new, original, and ornamental Design for Hosiery, of which the following is a specification, reference being had to the accompanying drawing, forming part thereof.

Figure 1 is a side elevation of a stocking showing my new design,

Fig. 2 is a rear elevation of the same.

I claim:

The ornamental design for hosiery, as shown.

JOHN P. NISSEN.
